Specification for Design.

Patented Mar. 23, 1920.

Application filed July 12, 1919. Serial No. 310,489. Term of patent 3½ years.

To all whom it may concern:

Be it known that I, LAZAR SELIBER, a citizen of Russia, residing at No. 28 Beach 113th street, Rockaway Park, Queens county, New York, have invented a new, original, and ornamental Design for Memorial-Plaques, of which the following is a specification, reference being had to the accompanying drawing, forming part hereof.

The figure is a front view of a memorial plaque showing my new design.

I claim:

The ornamental design for a memorial plaque as shown.

In testimony whereof I have hereunto set my hand on this 27th day of June, A. D., 1919.

LAZAR SELIBER.
